DESIGN FOR A FISHING NET

Melvin J. Meek and Bernard C. Hagquist,
South Bend, Ind.

Application September 15, 1945, Serial No. 122,107

Term of patent 14 years

(Cl. D31—4)

To all whom it may concern:

Be it known that we, Melvin J. Meek and Bernard C. Hagquist, citizens of the United States, residing at South Bend, in the county of St. Joseph, State of Indiana, have invented a new, original, and ornamental Design for a Fishing Net, of which the following is a specification, reference being had to the accompanying drawing, forming part thereof.

Fig. 1 is a top plan view of a fishing net, showing my new design.

Fig. 2 is an enlarged view of the handle of the fishing net in side elevation.

Fig. 3 is a cross-sectional view taken on line 3—3 of Figure 2.

We claim:

The ornamental design for a fishing net, as shown.

MELVIN J. MEEK.
